HOISTING DEVICE

Harry L. Berkey, Marion Center, Pa.

Application April 27, 1933, Serial No. 668,265

3 Claims. (Cl. 254—75)

The present invention appertains to new and useful improvements in means for lifting heavy loads, wherein the step by step principle of fulcrum and lever is employed.

The principal object of the present invention is to provide a novel hand tool which can be employed efficiently for handling heavy loads, the device affording a powerful leverage and having a much more universal use than devices of this character now in general use.

Another important object of the invention is to provide a hand tool of the hoist line type, wherein the parts are of strong, positive acting construction and not susceptible to the development of ready defects.

Other important objects and advantages of the invention will become apparent to the reader of the following specification.

In the drawings:—

20 Figure 1 represents a side elevational view of the tool in a position ready to start a cycle of operation.

Figure 2 represents a side elevational view of the tool after the lever has been moved downwardly a short distance.

Figure 3 represents a side elevational view of the tool after the lever has been moved downwardly its full extent.

Figure 4 represents a side elevational view of the tool with the lever moved upwardly towards completing the other half cycle.

Figure 5 represents a side elevational view of the tool just after the claw on the right has disengaged and with the lever moved upwardly to its full extent.

Figure 6 represents a side elevational view of the tool about ready to start the second cycle of operation and with the left claw engaged with the chain.

40 Figure 7 represents a top plan view of the tool.

Figure 8 represents a perspective view of one of the claw heads.

Referring to the drawings wherein like numerals designate like parts, it can be seen in Figure 1 that the tool includes an elongated hand lever 5 having a yoke 6 at one end thereof. A pair of elements 7—7 of substantially bell crank construction each has its intermediate portion secured to a shaft end, there being two shafts 8—8 which extend through the yoke 6, each being provided with an outstanding claw 9. Each of these claws is provided with a slotted claw head 10 and a pair of closely spaced guide flanges 11 inwardly of the head whereby the links of the chain 12 are guided.

55 A plate 13 is secured to one side of the clevis 21

by a suitable securing element 14 and has its intermediate portions spaced from the clevis. This plate 13 has an inverted Y-shaped slot 15 therein. A pair of link members 16—16 each has an opening at one of its ends to receive a pin 17 which rides in the Y-shaped slot 15, while their remaining ends are pivotally secured, as at 18, to the lower ends of the aforementioned bell cranks 7. The remaining upper ends of these bell cranks have coiled extensible springs 19 interposed between the same and the studs 20 on the head portions 10 of the claws 9.

Numeral 21 represents a clevis to which the plate 13 is secured, this clevis being swingably connected to the yoke 6, as at 22. The clevis 21 suspends an eyelet 23 which is connected to the lifting hook 24 by a ring 25. Obviously, when the handle 5 is moved downwardly from the position shown in Figure 1, the clevis 21 is being lifted, and the latter in turn lifting its load, and this lift continues until the hand lever 5 reaches the position shown in Figure 3, whereupon the reverse motion of the lever 5 is started and almost instantly the pin 17 rides out of the uppermost part of the Y-shaped slot 15 and rides into the diverged slot toward the left, which, due to the spring connection 26 between the two pivot points 18—18, causes a snapping action of the corresponding bell crank 7 so that the claw on the left is thrown toward the chain 12 and engages the same in the manner substantially shown in Figure 4. The lever is now continued upwardly and in so doing, the claw on the left in the drawings carries the chain toward the left and this results in the shifting of the pin 17 from one of the slot extensions to the other slot extension, thus causing a tripping action of the claw on the left, so that this last mentioned claw is thrown away from the chain and by moving the lever downwardly again to a position corresponding to the position shown in Figure 1, the claws are in a position to start another cycle of operation.

While the foregoing specification sets forth the invention in specific terms, it is to be understood that numerous changes in the same, size and materials may be resorted to without departing from the spirit and scope of the invention as claimed hereinafter.

Having described the invention, what is claimed as new is:—

1. A hoisting tool of the character described comprising a hand lever having a yoke, a pair of swingable claws on the yoke, bell cranks carried

105

110

by the yoke, said bell cranks being swingable on the yoke, a spring interposed between one end of each of the bell cranks and a corresponding claw, a spring connection between the remaining ends of the bell cranks, a clevis suspended from the yoke and center changing means interposed between the said clevis and the said bell cranks.

2. A hoisting tool of the character described comprising a hand lever having a yoke, a pair of swingable claws on the yoke, bell cranks carried by the yoke, said bell cranks being swingable on the yoke, a spring interposed between one end of each of the bell cranks and a corresponding claw, a spring connection between the remaining ends of the bell cranks, a clevis suspended from the yoke and center changing means interposed between the said clevis and the said bell cranks, said means comprising a pair of diverging slots on the clevis, link members extending toward the clevis from the spring connected ends of the bell cranks and a pin for pivotally connecting the

inner ends of the links together, said pin being operative in the said slots.

3. A hoisting tool of the character described comprising a hand lever having a yoke, a pair of swingable claws on the yoke, bell cranks carried by the yoke, said bell cranks being swingable on the yoke, a spring interposed between one end of each of the bell cranks and a corresponding claw, a spring connection between the remaining ends of the bell cranks, a clevis suspended from the yoke, center changing means interposed between the said clevis and the said bell cranks, said means comprising a pair of diverging slots on the clevis, link members extending toward the clevis from the spring connected ends of the bell cranks and a pin for pivotally connecting the inner ends of the links together, said pin being operative in the said slots, said clevis being provided with a notch at the merging point of the said slots for centering the claws when the pin engages therein.
